UNITED STATES PATENT OFFICE.

ERNEST JOHN RAWLINGS, OF BALHAM, LONDON, ENGLAND.

SPRING-ACTUATED WINDING MECHANISM, PARTICULARLY FOR WINDOWS.

Application filed September 12, 1922. Serial No. 587,801.

To all whom it may concern:

Be it known that I, ERNEST JOHN RAWLINGS, subject of the King of Great Britain, residing at Balham, London, England, have 5 invented a new and useful Improvement in and Relating to Spring-Actuated Winding Mechanism, Particularly for Windows, of which the following is a specification.

This invention relates to spring actuated 10 winding mechanism, and has particular reference to window raising mechanism for automobiles or other vehicles. Mechanism of this kind is known comprising a coil spring enclosed in a hollow roller or barrel 15 on which is wound a cord or cords attached to the window, and means for braking or holding and releasing the window at will so as to arrest the spring action and fix the window at any desired height. Difficulties 20 however are experienced in arranging within the width of an ordinary door or window a coil spring of sufficiently regular power the tendency being for the spring to be wound unduly tight when the window is down and 25 insufficiently powerful to take the weight of the window when it is up. There is also a tendency for the brake mechanism to permit creeping of the window and to interfere unduly with the weight and general design 30 appearance and fittings of the window frame or door frame in which the window moves. The chief object of the present invention is to provide a light, simple and reliable mechanism free from the above 35 mentioned defects.

A feature of the present invention consists 40 in the employment of a coil spring composed of a number of separate and distinct coiled segments connected in series and arranged the one within the other the respective segments being composed of wires of relatively graduated gauge the outermost segment being of wire of thickest gauge. The result of this is that when the barrel 45 is turned in a direction to stiffen the entire spring each segment will experience a proportional partial stiffening and will partake in the resultant effect. Such a spring has the coiling capacity of the sum of the 50 segments but occupies only the space of the largest or outermost, and can be housed in a barrel considerably shorter than the average width of a door or window frame.

In actual practice I find that three concentric helical coil segments arranged in 55 series one within the other with clearance

between them gives very satisfactory results although of course I may employ only two or more than three segments.

A spring and barrel arrangement as above 60 described in conjunction with a cord or cords attached to the barrel and the window operates to automatically raise the window as is well known, and various devices are also known for holding the window at any 65 desired height. The means I prefer to employ in accordance with the present invention operate with a strut-like action and I arrange the strut-like member employed for the purpose so that it or they become subjected to compression by spontaneous creeping 70 up or creeping down of the window or by both movements.

In order that the invention may be clearly understood and readily carried into effect I 75 will now describe the same more fully with reference to the accompanying drawings in which:—

Figure 1 is a front elevation of a sashless window partly lowered in its frame and 80 provided with my improved raising and braking mechanism.

Figure 2 is a longitudinal section of the 85 spring barrel arrangement on an enlarged scale.

Figures 3 and 4 are cross sectional elevations on the lines 3—3 and 4—4 respectively of Figure 2.

Figure 5 is a cross sectional elevation of a modified strut-like arrangement for braking 90 the window.

Figure 6 is a cross sectional elevation of a strut like arrangement acting to brake the window against movement both up and down.

In the drawings the invention is shewn applied to a sashless window such as is usually employed in certain types of automobile doors, but it is to be understood that it applies equally to windows mounted in sashes 100 and used in other circumstances as for example in railway carriages.

The glass window 1 glides in channels 2 in the door frame 3 and is provided with a handle or finger piece 4 at its upper edge and 105 with a bracket 5 carrying two small guide pulleys 6 at its lower edge. 7 is the barrel containing the multiple spring and having wound upon its surface the cord 8 which is secured at its ends to the barrel and passes 110 around the same and under the guide pulleys 6. The particular construction of mul-

multiple spring shewn in Figure 2 comprises three concentric helical coil segments 9, 10, 11 the outermost segment being of thick gauge wire the intermediate segment of intermediate gauge wire and the innermost segment of small gauge wire but obviously in practice two such segments or more than three could be used. The adjacent ends of the segments are connected together by suitable end caps or ferrules 12 of two diameters corresponding to those of the adjacent coil ends that they connect. The free end of the outermost spring 11 is connected to the barrel and the free end of the innermost spring 9 is connected to the barrel spindle 13 which is held against rotation by a ratchet arrangement hereinafter described. The initial tension of the spring may be regulated by turning the spindle 13 by a nut or squared portion 14 on it. The fixing of the ends of the coil segments to the end caps 12 is conveniently effected by forming coarse threads on the caps so that the end convolutions of the coil segments engage therewith like a nut on a screwthreaded bolt.

A multiple coil spring and barrel arrangement as above described presents so large a winding or coiling capacity that it affords a substantially constant or even force throughout the raising and lowering movements of the window so that no fusee or equivalent leverage varying device is necessary although such a device may be employed if desired. Moreover it can be of so inconspicuous a diameter and of such short length that it can be mounted in a cut-away or recessed portion of the cross or garnish rail 13 as shewn in Figure 1 without interfering with the normal structure or occupying abnormal space or preventing the usual lock or other arrangements near or on the rail from being fitted. The entire spring and barrel arrangement may be so moderate in size and so light in weight that it does not add materially to the bulk or weight of the door or frame in which it is fitted. One distinct advantage when fusees are dispensed with is that the cord winds directly on the barrel so that the exact position of the convolutions on the barrel is immaterial as well as the exact point of attachment of the cord to the window and moreover the entire barrel can be arranged within only a very small distance away from the face of the window. An increased leverage effect equivalent to using a fusee but retaining the before mentioned advantage can be obtained by using a cylindrical sleeve 14 slightly coned at its ends and mounted on the barrel as shewn in Figure 2, or the barrel itself can be tapered or otherwise shaped.

For the purpose of exerting a pressure or braking effect upon the window to prevent rattling and spontaneous creeping of the window upwards or downwards any suitable

pressure applying means may be employed. Preferably, however, I employ means having a strut-like effect as shewn in Figures 3 and 4 or Figures 5 or 6. These constructions comprise rockable arms 15 acting like short struts. They are located at each end of the barrel and are constituted by the upturned ends of a horizontal bar 16. The entire bar 16 with its up-turned ends or arms 15 is mounted to rock about the axis of the barrel spindle thereby enabling the padded tips 17 of the arms 15 to come into contact with the face of the window or move away therefrom by the rocking of the bar 16. The angle at which the arms 15 are set is such that the said arms act as short inclined struts so that the greater the tendency of the window to move the greater becomes the resisting pressure of the tips 17 of the arms upon the window. In Figures 3 and 4 this strut-like action occurs to prevent a downward creeping of the window and in Figure 5 it occurs to prevent an upward creeping of the window. In most cases the degree of pressure applied to the window by the tips 17 is quite sufficient to prevent rattling and accidental upward or downward movement of the window the strut-like action only being brought into play under exceptional circumstances or in windows having an abnormal tendency to spontaneously rise or fall but to ensure against any abnormal tendency in either direction the double strut arrangement shewn in Figure 6 may be employed. In this construction it is seen that a second arm 18 is pivoted at 19 to the brackets or framework 19^x by which the entire barrel arrangement is held in position. This arm 18 is normally thrust against the window by a spring 20 and the arm 15 is provided with a stop or lug 21 adapted to make contact with the arm 18 and press it away from the window when said arm 15 is rocked counterclockwise. Consequently the arms 15 and 18 either press upon the window together or move away therefrom together.

For the purpose of rocking the horizontal bar 16 with its arms 15 any convenient means such as a turn button or press button may be employed. The means I have shown for this purpose comprise a turn button or knob 22 having a quick thread working in a screw-threaded hole in a lug or boss 23 on the underside of the bar 16. It is evident that the turning of the knob 22 and from rocks the bar 16 and thereby causes the application or release of pressure on the window.

The holding of the barrel against rotation when the springs are being wound up to their normal tension by turning the spindle 13 at its squared portion 14 comprises a ratchet wheel 24 on the other end of the said spindle and a pawl 25 pivoted on the adjacent arm 15. It is to be noted that owing to

the tendency of the barrel to rotate and carry the spindle and ratchet wheel with it there is a pressure constantly transmitted through the pawl 25 to the arms 15 urging 5 their padded ends towards the window. As already described, the pressure on the window is regulated when required by operating the knob 22. Obviously however such spring applied pressure although advanta- 10 geous and very simply obtained is not essential to the operation of the arms 15. The arms 15 may have separate springs or no spring whatever and in the latter case the pawl 25 may be mounted on the fixed 15 bracket or framework 19* as shewn in Figure 5.

The padded tips 17 of the arms 15 may be of any convenient material and shape, being preferably curved slightly on their face as 20 shewn.

What I claim is:—

1. In winding mechanism of the spring barrel type, a helical spring composed of a plurality of segments concentrically ar- 25 ranged in series the one within the other and of different gauge wire, the innermost segment being of smallest gauge wire and the outer segment or segments being of wire of greater or successively greater gauge.

2. In winding mechanism of the spring barrel type, a helical spring composed of three segments concentrically arranged the one within the other and of different gauge wire, the outermost segment being of 35 thickest gauge wire, the intermediate segment of intermediate gauge wire, and the innermost segment of thinnest gauge wire, and means connecting adjacent ends of the springs in series.

3. In window raising mechanism of the spring barrel type, the combination with the barrel and the barrel spindle, of a helical spring structure operatively connected to said barrel and spindle, said spring structure 45 comprising a plurality of separate concentrically arranged helical wire spring segments so differing from one another in wire gauge that each segment experiences a proportional partial stiffening in the 50 resultant effect of any spring-stiffening movement as between the barrel and the spindle.

4. In winding mechanism of the spring barrel type, the combination with the barrel 55 and barrel spindle, of a helical spring structure operatively connected to said barrel and spindle, said spring structure comprising a plurality of separate helically coiled spring segments arranged con- 60 centrically one within the other and composed of wires of different gauge, the outermost being of thickest gauge wire, and connecting means intermediate said segments to serially connect them.

5. In winding mechanism of the spring

barrel type, the combination with the barrel and barrel spindle, of a helical spring structure operatively connected to said barrel and spindle, said spring structure comprising a plurality of concentrically 70 arranged separate helically coiled spring segments occupying a space which in width is substantially that of only one segment and composed of wires of different gauge, the outermost being of thickest gauge wire, 75 and connecting means intermediate said segments to serially connect them.

6. In window raising mechanism of the spring barrel type, a helical spring composed of a plurality of separate helical 80 spring segments arranged concentrically to occupy only the space of the outermost segment and composed of wire of different gauge, the outermost segment being of thickest gauge and the inner segments of 85 successively thinner gauge, and means connecting the adjacent ends of the segments in series, the outer end of the outermost segment being connected to the barrel and the further end of the innermost segment 90 being connected to the barrel spindle.

7. In window raising mechanism of the spring barrel type the combination with the barrel and barrel spindle, of a helical 95 spring composed of a plurality of helical spring segments arranged concentrically the one within the other in the space occupied only by the outermost segment and composed of wires of different gauge, the outermost being of thickest gauge and 100 the inner of successively thinner gauge, and screw threaded double-diametered ferrules rotatable on the barrel spindle and connected to adjacent ends of the spring segments by screw-threading engagement with 105 their convolutions to serially connect them.

8. A spring actuated window comprising a barrel, a barrel spindle, a helical spring operatively connecting the barrel and spindle, said spring comprising a plurality 110 of serially connected concentric helical spring segments differing in gauge and arranged to occupy the space only of the outermost segment which is of thickest gauge, a cord connecting the window proper 115 with the barrel, and a tapering sleeve secured on the exterior of said barrel for the winding-on of the cord.

9. A spring actuated window comprising a barrel, a barrel spindle, a helical spring 120 operatively connecting the barrel and spindle, said spring comprising a plurality of serially connected concentric helical spring segments differing in gauge and arranged to occupy the space only of the outermost segment which is of thickest gauge, a cord connecting the window proper 125 with the barrel, and means for holding the window at any desired height.

ERNEST JOHN RAWLINGS.
